CLAIM

The ornamental design for an electrical connector assembly, as shown and described.

DESCRIPTION

FIG. 1 is a top and front perspective view of the female connector of the electrical connector assembly according to the claimed design;

FIG. 2 is a top and back perspective view of the female connector of the electrical connector assembly according to the claimed design;

FIG. 3 is a bottom and front perspective view of the female connector of the electrical connector assembly according to the claimed design;

FIG. 4 is a bottom and back perspective view of the female connector of the electrical connector assembly according to the claimed design;

FIG. 5 is a front view of the female connector of the electrical connector assembly according to the claimed design;

FIG. 6 is a back view of the female connector of the electrical connector assembly according to the claimed design;

FIG. 7 is a left side elevational view of the female connector of the electrical connector assembly according to the claimed design;

FIG. 8 is a right side elevational view of the female connector of the electrical connector assembly according to the claimed design;

FIG. 9 is a top view of the female connector of the electrical connector assembly according to the claimed design;

FIG. 10 is a bottom view of the female connector of the electrical connector assembly according to the claimed design;

(Continued)

FIG. 11 is a top and front perspective view of the male connector of the electrical connector assembly according to the claimed design;
 FIG. 12 is a top and back perspective view of the male connector of the electrical connector assembly according to the claimed design;
 FIG. 13 is a bottom and front perspective view of the male connector of the electrical connector assembly according to the claimed design;
 FIG. 14 is a bottom and back perspective view of the male connector of the electrical connector assembly according to the claimed design;
 FIG. 15 is a front view of the male connector of the electrical connector assembly according to the claimed design;
 FIG. 16 is a back view of the male connector of the electrical connector assembly according to the claimed design;
 FIG. 17 is a left side elevational view of the male connector of the electrical connector assembly according to the claimed design;
 FIG. 18 is a right side elevational view of the male connector of the electrical connector assembly according to the claimed design;
 FIG. 19 is a top view of the male connector of the electrical connector assembly according to the claimed design;
 FIG. 20 is a bottom view of the male connector of the electrical connector assembly according to the claimed design;
 FIG. 21 is a top perspective view of the electrical connector assembly according to the claimed design;
 FIG. 22 is a top and side perspective view of the electrical connector assembly according to the claimed design;
 FIG. 23 is a top, front and right side perspective view of the electrical connector assembly according to the claimed design;
 FIG. 24 is a top, front, and left side perspective view of the electrical connector assembly according to the claimed design;
 FIG. 25 is a bottom and front perspective view of the electrical connector assembly according to the claimed design; and,
 FIG. 26 is a top and back perspective view of the electrical connector assembly according to the claimed design.
